DESIGN FOR A CURLING COMB

Elsa C. Ruckdeschel, New York, and William N. Brady, Piermont, N. Y., assignors to American Hard Rubber Company, New York, N. Y., a corporation of New York

Application June 11, 1937, Serial No. 69,792

Term of patent 14 years

To all whom it may concern:

Be it known that we, Elsa C. Ruckdeschel and William N. Brady, citizens of the United States and residents, respectively, of New York, in the county and State of New York, and Piermont, in the county of Rockland and State of New York, have invented a new, original, and ornamental Design for a Curling Comb, of which the following is a specification, reference being had to the accompanying drawing, forming a part thereof, and in which:

Fig. 1 is a side elevation of a comb embodying our new design, the reverse side of the comb being substantially of the same appearance as the side shown; Fig. 2 is a top plan of the comb shown in Fig. 1; and Figure 3 is an enlarged cross-sectional view taken on line 3—3 of Figure 1.

We claim:

The ornamental design for a curling comb as shown and described.

ELSA C. RUCKDESCHEL.
WILLIAM N. BRADY.
